UNITED STATES PATENT OFFICE

156,491

KITCHEN CABINET

Ethel G. Durkin, Santa Monica, Calif.

Application July 19, 1948, Serial No. 147,667

Term of patent 14 years

(Cl. D33—19)

To all whom it may concern:

Be it known that I, Ethel G. Durkin, citizen of the United States, residing at 1302 Fifth Street, Santa Monica, in the county of Los Angeles and State of California, have invented a new, original, and ornamental Design for Kitchen Cabinet, of which the following is a specification, reference being had to the accompanying drawing, forming part thereof.

Fig. 1 is a perspective view of a kitchen cabinet, showing my new design;

Fig. 2 is a front elevation view thereof;

Fig. 3 is a rear elevational view; and

Fig. 4 is a sectional view taken on line 4—4 of Fig. 1.

I claim:

The ornamental design for a kitchen cabinet, as shown.

ETHEL G. DURKIN.
